Primary Examiner — Mary Ann Calabrese*(74) Attorney, Agent, or Firm* — Oppenhuizen Law PLC;
David L. Oppenhuizen(57) **CLAIM**

The ornamental design for a table base, as shown and described.

DESCRIPTION

FIG. 1 is a perspective view of a table base showing the new design;

FIG. 2 is a front view, the back view being a mirror image thereof;

FIG. 3 is a left view, the right view being a mirror image thereof;

FIG. 4 is a top view;

FIG. 5 is a bottom view;

FIG. 6 is a perspective view of a second embodiment of the table base;

FIG. 7 is a front view of the second embodiment of the table base, the back view being a mirror image thereof;

FIG. 8 is a left view of the second embodiment of the table base, the right view being a mirror image thereof;

FIG. 9 is a top view of the second embodiment of the table base; and,

FIG. 10 is a bottom view of the second embodiment of the table base.

The broken lines are included for the purpose of illustrating portions of the table base that form no part of the claimed design.

1 Claim, 6 Drawing Sheets(56)
